CLOSURE CAP FOR THE ACCESS PORT OF A WATER SOFTENER TANK

James E. McAuley, Compton, Calif., assignor to California Manufacturing and Equipment Company, Los Angeles, Calif., a corporation of California

Application September 16, 1957, Serial No. 47,758

Term of patent 14 years

(Cl. D16—2)

FIG. 1.

FIG. 2.

FIG. 3.

Figure 1 is a side elevational view of the closure cap for the access port of a water softener tank showing my new design;

Figure 2 is a top plan view of the closure cap; and

Figure 3 is a transverse sectional view taken along line 3—3 on Figure 2.

The broken line showing in Figure 1 is for illustrative purposes only.

I claim:

The ornamental design for a closure cap for the access port of a water softener tank, substantially as shown and described.
